Mass., a corporation of Delaware

Application March 13, 1947, Serial No. 734,470

8 Claims. (Cl. 257—128)

1

The present invention relates to heat exchangers and methods of assembling the same, and is more particularly concerned with heat exchangers having thin-wall closely spaced tubes such as are used for aircraft oil coolers.

The oil cooler described in the Woods application Serial No. 603,491, filed July 6, 1945, comprises a cooler having longitudinal baffles to provide axial flow paths through the coolers. The core comprises a set of closely spaced thin wall tubes, preferably of aluminum. In the preferred form of the invention the tubes are brazed to the aluminum headers. The baffles are inserted in suitable spaces on the sides of the core. As described in said application, each baffle is sealed to one of the headers. The particular construction there described involving the use of a rubber-like sealing member. The oil cooler specifically described in that application is a demountable cooler, namely one in which the baffles may be removed for cleaning purposes although a similar arrangement may be used for a heat exchanger which is not intended to be disassembled.

The object of the present invention is to provide improvements in methods and means for sealing the baffles in heat exchangers of this general type. To this end the present invention comprises the heat exchanger hereinafter described and particularly defined in the claims.

In the accompanying drawings, Fig. 1 is a sectional view of a heat exchanger core according to the present invention; Fig. 2 is a section on line 2—2 of Fig. 1; Fig. 3 is an enlarged detail view taken on line 3—3 of Fig. 1; Fig. 4 is an enlarged end view of the parts shown in Fig. 3; Fig. 5 is a detail showing the preparation of the sealing foil; Fig. 6 is a perspective view showing the application of the sealing foil; and Fig. 7 is a view showing the construction of the filling material to prevent channeling.

The construction shown in the drawings comprises a core consisting of a large number of closely spaced thin wall tubes 10 protruding at opposite ends through header plates 12. Each header plate is provided with a circumferential flange 14 for attachment to a shell as will hereinafter be described. To illustrate the size and spacing of the tubes, each tube may be about .268" in diameter and of a wall thickness of about .005", spaced .313" on centers. The tubes are preferably of aluminum. The tubes are brazed to the headers by the method described in the Woods Patent No. 2,389,175 dated November 20, 1945.

As shown in Fig. 1, the tubes are arranged in

2

groups. Between adjacent groups there is a space 16 preferably about .085" to accommodate the baffles. Five of such spaces are provided so that the cooler has six axial-flow passages. A completed cooler may have 3600 tubes or more, but for simplicity a relatively small number are shown in the drawing. Baffles 18 are inserted in the spaces 16. Each baffle 18 comprises an aluminum sheet of about .025" thick. Each baffle is provided with pressed spacer projections 20, protruding in both directions from the sheet to engage with tubes on opposite sides. Each baffle is the proper width to extend across a chord of the core and is provided with wings 22 which can be readily bent for engagement with the shell. The baffles are of less height than the wings to provide an oil flow space 24. One edge of each baffle is adapted to be sealed against one of the headers, and the space 24 provides an oil-flow passage between the groups of tubes of the cooler. The oil-flow space 24 is arranged at opposite ends of the cooler for alternate baffles as will be obvious to those skilled in the art, in order that the oil will be caused to flow along the six groups of tubes in series.

It is important that the edge of the baffle opposite the space 24 be tightly sealed to the header. It is impracticable to braze the baffle to the header after insertion of the tubes since such an operation would require dipping of the core into molten brazing material with consequent danger of destroying some of the tubes. Furthermore, it is desirable to provide a construction which can be taken apart if desired.

According to the present invention, the baffles are inserted into the spaces 16 after the tubes are assembled in the headers. The lengths of the wing portions 22 and the sizes of the positioning projections 20 are such that the baffles may readily be inserted.

To seal the edge against the header, a mass of metal foil is applied. This is conveniently applied by passing a thin roll of foil into the space between the edge of the header and a row of tubes.

As shown in Fig. 5, a sheet of foil 26 is rolled up on a thin metal strip 28. The foil is only about .001" thick and several convolutions will produce only a thin roll but it will be understood that the thickness is necessarily exaggerated in the drawing. The roll of foil, still mounted on the bar 28, is then inserted into the space 16 at one side of the baffle. The roll is of the correct length to reach across a chord of the header. The bar 28 is then removed leaving the roll of foil against the header. Another bar 30, preferably somewhat

thicker than the bar 28, is inserted into the space above the roll of foil and is of sufficient length so that the operator can grasp it at both ends. This is shown in Fig. 6. The operator then presses down on the bar 30 thus mashing the foil against the header and between the baffle and the adjacent row of tubes. As shown in Figs. 2, 3 and 4, the foil mashes down in such a way as to partially surround some of the tubes, thus providing a tight interlock.

This operation is repeated several times until a substantial amount of foil has been built up. Preferably a sufficient amount of foil is introduced to build up a compacted mass to a depth of $\frac{1}{8}$ " or more.

Owing to the process of manufacture, some of the header plates may be bowed or dished in one direction or the other. It will be understood that by repeated application of rolls of foil, a sufficient body of packed or massed foil may be built up to fill any spaces due to distortion of the header. The mass of foil is firmly locked in place; it secures the baffle firmly in position and forms an oil-tight seal which cannot be weakened or destroyed in normal service.

If at any time it is necessary to remove a baffle, the foil can be worked out by introducing a thin hook-shaped pointed instrument into the space between the baffle and the tubes. By furring up the foil and pulling out a little at a time, it is possible to remove the foil sufficiently to permit the baffle to be drawn out.

After insertion of the baffles, the wings 22 protrude somewhat beyond the edges of the flanges 14. The wings are bent over slightly as shown in Fig. 1. The tank or shell 32 is ultimately to be slipped over the core.

Prior to application of the tank, however, it is necessary to close off the spaces near the edges, in order to prevent channeling of liquid. It will be understood that the holes in the header plates, being formed in rows, as shown in Fig. 1, cannot be arranged so that all the tubes will be sufficiently close to the shell. If the shell were applied without filling in such spaces, excessive channeling of liquid between the outer tubes and the shell might occur. The filling material 33 preferably comprises several tubes 34 arranged in a row and held together with caps 36 made by folding foil around their ends, as shown in Fig. 7. The tubes 34 are preferably of a soft alloy so that they can be jammed into place against the tubes of the core; the foil 36 is similar to, but heavier than, the foil 26. The tubes 34 may have small openings punched near opposite ends to allow any liquid that may get inside to drain out of the tubes.

The filling tube assemblies 33 are pressed into place around the core and between the baffles. Then the wings 22 are bent to lock the filling tube assemblies in place and also to allow the tank or shell 32 to be slipped over the core. The tank may be of any suitable form but as shown in Fig. 2 it is provided the usual casting 38 to accommodate the control valve assembly. The inside diameter of the tank is such as to slide over the flanges 14 of the headers. The tank is started over one header and is pushed down along the wings 22. The resiliency of the wings causes them to fit tightly against the tank. The tank may be secured to the headers by any of the fastening means shown in the Woods application No. 603,491 or if the unit is not intended to be taken apart, the tank is preferably welded to the flanges as indicated by the ring weld 40.

Having thus described the invention, we claim:

1. Heat exchange apparatus comprising a core having a large number of closely spaced thin-wall tubes and headers through which the ends of the tubes project, baffles extending across the core between selected rows of tubes to form axial-flow passes, a mass of pressed foil for sealing one edge of each baffle against a header, the mass of foil extending the full length of the contacting edge between the baffle and the header, and being packed tightly against said edge, alternate baffles having said edge sealed against opposite headers, each baffle having a large oil-pass space at the edge opposite the sealed edge and having side portions extending between headers, a shell surrounding the core, and means for securing the shell to the headers.

2. Heat exchange apparatus comprising a core having a large number of closely spaced thin-wall tubes and headers through which the ends of the tubes project, baffles extending across the core between selected rows of tubes to form axial-flow passes, a mass of compacted pressed foil extending along one entire edge of each baffle to seal the baffle against a header, the foil being interlocked with adjacent tubes.

3. Heat exchange apparatus comprising a core having a large number of closely spaced thin-wall tubes and headers through which the ends of the tubes project, baffles extending across the core between selected rows of tubes to form axial-flow passes, a mass of pressed foil for sealing one edge of each baffle against a header, the mass of foil extending the full length of the contacting edge between the baffle and the header, and being packed tightly against said edge, alternate baffles having said edge sealed against opposite headers, each baffle having a large oil-pass space at the edge opposite the sealed edge and having bent wing portions extending outwardly beyond the headers, a shell surrounding the core and engaging the wing portions of the baffles throughout their length, and means for securing the shell to the headers.

4. Heat exchange apparatus comprising a core having a large number of closely spaced thin-wall tubes and headers through which the ends of the tubes project, baffles extending across the core between selected rows of tubes to form axial-flow passes, a mass of compacted pressed foil extending along one edge of each baffle to seal the baffle against a header, the mass of foil extending the full length of the contacting edge between the baffle and the header, and being packed tightly against said edge, the foil being interlocked with adjacent tubes, alternate baffles having said edge sealed against opposite headers, each baffle having a large oil-pass space at the edge opposite the sealed edge and having bent wing portions extending outwardly beyond the headers, a shell surrounding the core and engaging the wing portions of the baffles throughout their length, and means for securing the shell to the headers.

5. Heat exchange apparatus comprising a core having a large number of closely spaced thin-wall tubes and headers through which the ends of the tubes project, baffles extending across the core between selected rows of tubes to form axial-flow passes, a mass of pressed foil for sealing one edge of each baffle against a header, the mass of foil extending the full length of the contacting edge between the baffle and the header, and being packed tightly against said edge, alternate baffles having said edge sealed against opposite headers,

each baffle having a large oil-pass space at the edge opposite the sealed edge and having bent wing portions extending outwardly beyond the headers, filling material applied to the core adjacent the edges thereof and between the wing portions of the baffles, said filling material comprising a row of tubes and foil-like caps for the tubes, a shell surrounding the core and engaging the wing portions of the baffles throughout their length, and means for securing the shell to the headers.

6. The method of making a baffled thin-wall tube heat exchanger which consists in inserting a baffle into the inter-tube space of a heat exchanger core, inserting a roll of metal foil wrapped on a thin bar at the joint between the header and baffle withdrawing said bar from the roll of foil, inserting a narrow bar above the roll of foil, and pressing downwardly on said bar to compact the foil firmly into said joint and substantially uniformly along the entire joint.

7. Heat exchange apparatus comprising a core having a large number of closely spaced thin-wall tubes and headers through which the ends of the tubes project, baffles extending across the core between selected rows of tubes to form axial-flow passes, a roll of foil compressed into the space along the line of contact of each baffle with a header for sealing the edge of said baffle against said header, the compressed roll of foil extend-

ing the full length of the contacting edge of the baffle with the header, alternate baffles having said edge sealed against opposite headers, each baffle having a large oil-pass space at the edge opposite the sealed edge and having side portions extending between headers, a shell surrounding the core, and means for securing the shell to the headers.

8. The method of making a baffled thin-wall tube heat exchanger which consists in inserting a baffle into the inter-tube space of a heat exchanger core, inserting a roll of metal foil wrapped on a thin bar at the joint between the header and baffle, withdrawing said bar from the roll of foil, and pressing the foil firmly into said joint.

Certificate of Correction

Patent No. 2,520,821

August 29, 1950

JOHN E. WOODS ET AL.

It is hereby certified that error appears in the printed specification of the above numbered patent requiring correction as follows:

Column 4, lines 71 to 74, strike out the words and comma "the mass of foil extending the full length of the contacting edge between the baffle and the header, and being packed tightly against said edge,";

and that the said Letters Patent should be read as corrected above, so that the same may conform to the record of the case in the Patent Office.

Signed and sealed this 12th day of December, A. D. 1950.
